UNITED STATES PATENT OFFICE.

WILLIAM H. ROGERS, OF LOOKOUT MOUNTAIN, TENNESSEE.

MAIL-BAG DELIVERER AND CATCHER.

No. 899,074.

Specification of Letters Patent.

Patented Sept. 22, 1908.

Application filed June 20, 1908. Serial No. 439,512.

To all whom it may concern:

Be it known that I, WILLIAM H. ROGERS, a citizen of the United States of America, and a resident of Lookout Mountain, county 5 of Hamilton, State of Tennessee, have invented certain new and useful Improvements in Mail-Bag Deliverers and Catchers, of which the following is a full and clear specification, reference being had to the accompanying drawings, in which—

Figure 1 is a plan view partly in section of the grab-hook; Fig. 2 is a plan view partly in section of the pouch-receiver adapted to be mounted on the roadbed; Fig. 3 is a section 15 through the line 3—3 of Fig. 1.

This invention has special reference to that class of mail - bag delivering and receiving devices covered by my former patent No. 882,345, dated March 17, 1908, and the object of the present invention is to improve and simplify the grab-hook on the car and to provide simple and practical means for preventing the pouch rebounding out of the hook or receiver on the roadbed, as more 25 fully hereinafter set forth.

Referring to the drawings by reference characters, *a* designates one of the doorposts of the car to which is attached a suitable bearing *b* in which is journaled the stub-shaft *c* of the grab-hook or receiver, this shaft being detachably held in its bearing by a thole-pin *d*. The forward end of the shaft is provided with a right angle offsetting arm *e* to the outer end of which is attached the two 30 arms *f* and *g* forming the mouth of the hook, the arms flaring outwardly in the usual manner and the inner arm being provided with a suitable handle *h* for turning the horizontal shaft *c* in its bearing.

With the above construction it will be observed that when the grab-hook is swung upwardly and outwardly into operative position it will stand away from the side of the car sufficiently to prevent the pouch striking 40 the car when it is received in the hook, and also that when the device is released from the hand of the operator it will swing downwardly and lie close to the side of the car out of the way.

To prevent the bag rebounding out of the

hook I provide a spring catch and attach the same to the inner face of one of the arms *f* or *g*. This spring consists of a straight portion *i* lying snugly in a longitudinal groove formed in the inner face of the arm and having its forward end extending transversely through a hole in the arm and threaded for the reception of a clamp nut *j*, whereby the arm is rigidly but removably fastened in place. The rear end of the arm is bent outwardly and rearwardly and then inwardly, forming a latch-like shoulder *k* extending partly across the throat of the hook at a suitable distance from its crotch. The inwardly extending portion *l* extends loosely 55 through a transverse hole in the arm and is formed at its inner extremity into a ring or hook *m*.

It will be observed that when a pouch passes into the crotch of the hook it will 60 force back the latch until it has passed the same whereupon the latch will spring outwardly and form an abutment which will prevent the pouch rebounding out of the hook. When the pouch is to be removed from the 65 hook the catch is drawn back by means of the finger-ring *m*. By embedding the front portion of the spring in a groove in the arm it will be observed that I avoid cutting or scoring the pouch as it passes into the crotch of 70 the hook while at the same time ample length of spring is obtained to insure the necessary resilience. The screw also enables the spring to be locked rigidly in place with but a single bolt without interfering with its 75 resilience.

In Fig. 2 I show the application of my spring catch to the double receiving-hook mounted on the roadway. In this receiver I prefer using a pair of the hooks in 80 each receiving crotch.

Having thus fully described my invention, what I claim as new and desire to secure by Letters Patent is:—

A mail pouch receiving device consisting 95 of a pair of diverging arms, one of the arms being provided with a spring latch consisting of a substantially straight portion lying in a groove in the inner face of the arm and having its forward end extending trans- 100

versely through the arm, a clamp nut on this transversely bent end, the rear end of said latch inclining rearwardly and outwardly into the throat of the receiver and being turned back through a transverse hole in the arm, the extremity being provided with a finger-hold.

In testimony whereof I hereunto affix my

signature in the presence of two witnesses this 15th day of June, 1908.

WILLIAM H. ROGERS.
